UNITED STATES PATENT OFFICE.

THOMAS C. JOHNSON, OF NEW HAVEN, CONNECTICUT, ASSIGNOR TO WINCHESTER REPEATING ARMS CO., OF NEW HAVEN, CONNECTICUT, A CORPORATION.

MUSHROOM-BULLET.

1,080,977.

Specification of Letters Patent.

Patented Dec. 9, 1913.

Application filed September 18, 1913. Serial No. 789,604.

To all whom it may concern:

Be it known that I, THOMAS C. JOHNSON, a citizen of the United States, residing at New Haven, in the county of New Haven 5 and State of Connecticut, have invented a new and useful Improvement in Mushroom-Bullets; and I do hereby declare the following, when taken in connection with the accompanying drawings and the characters of 10 reference marked thereon, to be a full, clear, and exact description of the same, and which said drawings constitute part of this application, and represent, in—

Figure 1, a view in side elevation of a 15 mushroom bullet constructed in accordance with my invention, a portion of the jacket being broken away exposing a portion of the core in section. Fig. 2, a corresponding view of one of the modified forms which 20 my invention may assume.

My invention relates to an improvement in full-jacketed, sharp-nosed mushroom bullets in which a relatively hard sheet-metal jacket is swaged upon and entirely filled 25 by a soft metal core, the object being to produce at a low cost for manufacture a superior bullet of the character described.

With these ends in view, my invention 30 consists in a mushroom bullet having certain details of construction as will be hereinafter described and pointed out in the claim.

In carrying out my invention, the relatively hard one-piece sheet-metal jacket 35 closed at its forward end, is virtually divided into a tip, 2, and a body, 3, by the formation in the exterior surface of the tip of a circumferential groove, 4, formed by cutting away and removing a portion of the 40 metal of the jacket without penetrating, however, to the core, 5, so that the bottom

wall, 6, of the groove is relied upon to hold the body and tip of the jacket together. The jacket, however, is so weakened by the cutting of the groove, 4, into it that it readily breaks down along the line of the groove 45 and permits the bullet to mushroom at the time of impact.

In the modified construction shown by Fig. 2, the jacket is virtually divided into a tip, 2, and a body, 3, by the formation in 50 the jacket of a groove, 7, of triangular cross-section and formed by cutting a portion of the metal of the jacket away without, however, cutting it through to the soft metal core, 5, the thin line of metal, 8, at the 55 bottom of the groove, 7, serving to hold the parts 2 and 3 of the jacket together. The groove 7, however, so weakens the jacket that it readily breaks down at the time of impact and permits the bullet to mushroom. 60

I claim:

A full jacketed, sharp-nosed mushroom bullet, comprising a one-piece sheet-metal jacket closed at its front end, and a soft-metal core, the jacket being virtually divided into a top-portion and a body-portion 65 by the formation on the exterior surface of its tapering point of a circumferential cut groove the bottom wall of which serves to unite the said tip and body portions of the 70 jacket, whereby the jacket is weakened by the said groove so as to readily mushroom on impact.

In testimony whereof, I have signed this specification in the presence of two subscribing witnesses. 75

THOMAS C. JOHNSON.
